(57) **CLAIM**

The ornamental design for an automated storage and retrieval vehicle, as shown and described.

DESCRIPTION

FIG. 1 is a front, top, left perspective view of a design for an automated storage and retrieval vehicle;

FIG. 2 is a rear, top left perspective view of the design for an automated storage and retrieval vehicle;

FIG. 3 is a front elevational view of the design for an automated storage and retrieval vehicle;

FIG. 4 is a plan view of the design for an automated storage and retrieval vehicle;

FIG. 5 is a right side elevational view of the design for an automated storage and retrieval vehicle with the left side elevational view being the same as the right side view;

FIG. 6 is a rear elevational view of the design for an automated storage and retrieval vehicle; and,

FIG. 7 is a bottom view of the design for an automated storage and retrieval vehicle.

Throughout the drawings, broken lines depict portions of the automated storage and retrieval vehicle that form no part of the design.

1 Claim, 7 Drawing Sheets
